UNITED STATES PATENT OFFICE.

WILLIAM H. RYER, OF STEELE CITY, NEBRASKA.

WATER-HEATING ATTACHMENT FOR DRUMS.

SPECIFICATION forming part of Letters Patent No. 427,798, dated May 13, 1890.

Application filed August 26, 1889. Serial No. 321,981. (No model.)

To all whom it may concern:

Be it known that I, WILLIAM H. RYER, a citizen of the United States, residing at Steele City, in the county of Jefferson and State of Nebraska, have invented certain new and useful Improvements in Water-Heating Attachments for Drums; and I do hereby declare that the following is a full, clear, and exact description of the same, reference being had to the annexed drawings, making a part of this specification, and to the letters of reference marked thereon.

This invention relates to certain new and useful improvements in water-heating attachments to stoves, stove-pipes, or drums; and it has for its object to provide a simple and cheap device of this character, which may be readily applied or detached, being made concave to conform to the convexity of the pipe or drum to which it is attached, so as to lie close to said pipe or drum and utilize what would otherwise be waste heat.

The invention consists in the peculiar combinations and the construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a perspective view illustrating my improvement applied to a stove-pipe or drum. Fig. 2 is a central vertical section through the same.

Referring to the details of the drawings by letter, A designates a tank or vessel of any suitable metal of tapering form, as shown, with the narrower end at the bottom to facilitate the heating of the water within the tank. The rear wall of this tank is concaved to conform to the convexity of the drum or pipe to which it is to be applied, as shown in the drawings, the outer wall being preferably convex, as shown, both for strength and beauty. Near its lower end this tank is provided with a faucet B to draw off the contents of the tank when necessary. Around the upper edge of the top of this tank is seamed a wire C, as shown, the upper edge of

the metal of the tank being rolled around the wire, as is common in metal vessels, for the purpose of strengthening the same. At the rear corners this wire has its ends extended, as shown at D, and bent upward and then forward to form the hooks E, by means of which the tank may be suspended upon a suitable support on the pipe or drum, as indicated in Fig. 1.

In the drawings I have shown this support to consist of a band or ring F, encircling the pipe or drum, which is indicated by the letter X, said band or ring being arranged to encircle the pipe or drum and held in its proper position in any suitable manner, in this instance shown as held to the drum or pipe by means of metallic clasps G, which may be either suitably secured to the outer wall of the pipe or drum, or may be made sufficiently rigid to hold the band in its position by frictional contact with the pipe or drum.

The tank is provided with a hinged cover or lid H, which has depending flanges I; to embrace closely the front and sides of the tank and prevent the escape of steam. This lid or cover has a suitable handle K, by which it may be readily lifted, the front wall of the tank also being provided with a suitable loop or handle L. On the bottom of the tank is secured a ring M, by means of which it may be hung up upside down when not in use.

In practice the tank is suspended on the pipe or drum, as shown, with its concave side embracing the drum or pipe, and the water which has been placed within the tank readily heated by the heat radiating from the pipe or drum. It may be used for heating water, boiling vegetables, or other purposes.

The device is simple, cheap, and in practice has proved very efficient for the purpose for which it is intended.

What I claim as new is—

1. A device for the purpose specified, consisting of a tank having its upper edge strengthened by a wire, the ends of which are extended and bent upward and then forward to form hooks to engage the suspension means, as the ring F, on the pipe or drum, as set forth.

2. The combination, with the stove-pipe and the metallic clasps G, secured thereto, of the ring F, held by said clasps, the tank having

concaved side to conform to the convexity of the pipe, and the strengthening-wire C, seamed around the upper edge of the tank, with its ends extended upward at the rear of the tank 5 and formed into hooks to detachably engage said ring, substantially as shown and described.

In testimony that I claim the above I have hereunto subscribed my name in the presence of two witnesses.

WILLIAM H. RYER.
